ATTORNEY.

UNITED STATES PATENT OFFICE.

ANGELINE SMELKER, OF NORTH STAR, OHIO, ASSIGNOR OF ONE-THIRD TO
MARY M. MEHRING, OF INDIANAPOLIS, INDIANA.

FRUIT-JAR CLOSURE.

SPECIFICATION forming part of Letters Patent No. 645,430, dated March 13, 1900.

Application filed September 11, 1899. Serial No. 730,132. (No model.)

To all whom it may concern:

Be it known that I, ANGELINE SMELKER, a citizen of the United States, residing at North Star, in the county of Darke and State of Ohio, have invented certain new and useful Improvements in Fruit-Jar Closures; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to the appliances employed in connection with the mouths of jars for closing and sealing the same after having been filled; and the invention consists in a jar-neck, a lid, and securing device of new 20 and novel form of construction and combination and arrangement of parts hereinafter described, and pointed out in the claims.

25 Objects of this invention are to provide a closure which shall be reliable and positive in use, so as to avoid leakage and consequent loss, which shall be adapted to be effective when either the lid or the jar-neck, or both, are inaccurately formed, as frequently occurs in practice, and which, furthermore, may be 30 cheaply produced and be durable and economical in use. These objects are attained in my invention and illustrated in the accompanying drawings, in which similar letters of reference throughout the several figures designate similar parts.

35 Referring to the drawings, Figure 1 represents a fragmentary perspective view of a fruit-jar embodying my invention; Fig. 2, a central vertical sectional view; Fig. 3, a central vertical sectional view of the lid, showing the packing-ring as it would appear when applied before being pressed down to form the sealing, the dotted lines *h h* indicating the opposing walls of the neck; Fig. 4, a central 40 vertical sectional view of the upper part of a jar having a neck formed in accordance with my invention; Fig. 5, an elevation of the lid; Fig. 6, a perspective view of the packing or sealing ring; Fig. 7, a central vertical sectional view of the securing screw-ring or lid-

retainer; Fig. 8, a top plan of the lid-retainer; Fig. 9, a vertical sectional view illustrating more clearly than in Fig. 2 the form assumed in cross-section by the sealing-ring when pressed down to effect the sealing or closure. 55

In practically carrying out my invention I employ jars or like vessels *A* of any suitable type and material, preferably of glass, in the form which is usually employed for preserving fruit, and I provide a neck *B* of suitable 60 size and form, at the top or mouth of which the lid *E* is applied. The lid is also preferably made of glass or similar substance, so that the contents of the vessel may not be contaminated by contact with metal, as in 65 some cases, and as it is difficult to accurately and cheaply form such material I apply the sealing or packing ring in a V-groove above the lid, and the whole arrangement is such that the sealing-ring adapts itself to the inequalities of surface of the unyielding lid and neck with which it forms a contact, as will be 70 further more clearly explained hereinafter.

While a screw-ring *G* is shown adapted to engage screw-threads *b* at the exterior of the 75 neck *B*, I may employ lugs and recesses whereby to lock the lid to the neck, all of familiar form.

The neck *B* is circular and has an internal 80 annular rib *a* situate a short distance below the top or mouth thereof for the purpose of supporting the lid, and above the rib is a sloping or annular face *C*, against which the sealing-ring *F* is forced to bear at the exterior 85 surface. The diameter of the annular face *C* is greatest at its top and may extend to the mouth of the vessel, if desired, forming the outer wall of the V-groove. The lid *D* is also circular and at its bottom *e* fits neatly upon the annular rib *a* and as closely as practicable to 90 the bottom of the sloping face *C*. Preferably the lid has a rib *f* at its bottom, fitting within the rib *a*, but it is not in all cases essential. It is designed to prevent the contents of the vessel from readily flowing between the bottom *e* and the top of the rib *a*. The periphery of the lid forms an annular beveled face *E*, sloping inwardly from the bottom *e*, so as to be smallest diametrically at the top of the 95 lid, providing the inner wall of the V-groove, 100

and against this face the internal surface of the sealing-ring F is forced. A knob d is provided for lifting the lid from the neck. It will be observed that the junction of the lid 5 and the neck is at the bottom of both sloping faces of the V-groove, so that there is no flat bottom to arrest the sealing-ring.

The sealing-ring F is circular and has sufficient area in cross-section to provide considerable elasticity to compensate for irregularity of the circular faces C and E, against which it bears to form the sealing. A circular cross-sectional form is preferable, as shown; but this may be slightly varied, as it 15 would be equally effective were it semicircular, with the circular part undermost in use. It should be made of rubber or of a composition of similar substance. The screw-ring G is also circular and near the top has an exterior milled groove J, in which a cord or wire clamp may be drawn taut in order to force the ring on and off the neck. The top of the screw-ring is open, but it has an internal flange H, which extends over the edge of the neck B 25 and downward at the inside of the neck, forming a depressed flange I, adapted to bear upon the sealing-ring F, by which construction the lid is somewhat depressed in the neck, so that the knob d does not protrude above the flange 30 H, which is a convenience when it is desired to set one jar upon another; but it is obvious that the flange II might be adapted to bear upon the sealing-ring with a slight modification in the position of the bearing-faces for 35 the sealing-ring. Yet the form shown, having a nearly-vertical part between the flange planes H and I, possesses the greatest strength with the minimum thickness or weight of material in the screw-ring, which may suitably 40 be made of either spun or pressed zinc.

In some cases it may be desirable to form either one or both of the faces C and E more nearly vertical than shown in order to economize in the use of the elastic material of which 45 the sealing-ring F is formed, and I therefore reserve the right as within the scope of my invention. Also the annular groove, which is formed by the faces C and E, may be semi-circular in cross-section instead of V-shaped, 50 as preferably formed.

In practical use, the jar being filled, the lid D is inserted, and then the sealing-ring F is placed in position in the V-shaped annular groove formed by the oppositely-sloping faces 55 C and E, and as the groove thus formed may be of greater width at some portions than at others, owing to inaccuracies in forming the parts, as is well known, the sealing-ring by reason of its large sensitive volume in cross-section readily adapts itself under slight pressure to the variations of surface and approximately forms contact continuously against both sides of the groove. The screw 60 or retaining ring G is placed in position; and 65 as it is forced against the top of the ring F

the latter, having the two annular points of contact below, is prevented from turning, the resistance at the top being slight at first, so that the metal slides freely upon it until sufficient force is exerted to flatten the top 70 and sides of the ring, as it would appear in cross-section, so as to resemble a triangle, the bearing-surfaces thus hemming in the elastic material as it spreads and insuring a tight joint, at the same time preventing an upward 75 movement of the lid. When opening the jar, the retaining or screw ring and the sealing-ring may be removed and laid away for future use, while the lid may be conveniently used with the jar while the contents are used 80 in small quantities from it, and thus has advantages appreciated by the housekeeper.

Having thus described my invention, what I claim, and desire to secure by Letters Patent, is—

1. A jar-closure comprising a neck provided with an internal annular sloping face extending downwardly and inwardly from the top of the neck, so as to form in transverse section substantially one-half of a vertically-divided V-shaped groove; a support for a lid at the bottom of the sloping face; a lid provided with an external annular sloping face extending upwardly and inwardly from the bottom of the lid, at the periphery thereof and embracing the whole of the periphery of the lid, so as to form in transverse section substantially one-half of a vertically-divided V-shaped groove; a sealing-ring bearing against both of the sloping faces only at the 95 portions thereof intermediately of their extremities; and a retaining-ring bearing upon the upper side of the sealing-ring; whereby a triple contact-joint is provided.

2. In a jar-closure, the combination of the 105 neck and the lid provided each with an oppositely-disposed sloping face forming one-half of a V-shaped annular groove parting centrally at the bottom thereof, a support for the bottom of the lid, a sealing-ring having 110 a contact with the sides of the groove intermediate the tops and bottoms thereof, and the retaining-ring bearing upon the top of the sealing-ring transversely centrally.

3. In a jar-closure, the combination of the 115 neck having the external lid-securing devices and the internal sloping annular face, the lid-support, the lid having the sloping peripheral face extending from the bottom of the lid upwardly, the sealing-ring bearing against 120 said sloping faces, the retaining-ring having the securing devices corresponding to the securing devices upon the neck, the parallel portion at the upper part of the neck above such securing devices, the continuous annular groove in the upper part of the retaining-ring registering with said parallel portion 125 and having milling or serrations transversely therein, and the depressed flange removed from such annular groove and bearing upon 130

the top of the sealing-ring in a plane below the top of the neck.

4. In a fruit-jar, a closure comprising the neck and the lid, the annular groove parted 5 centrally at the bottom thereof on a vertical line, a sealing-ring seated against the opposing sides of said groove intermediate of the tops and bottoms thereof only whereby bottom clearance is effected, and the retaining-

ring bearing upon the upper side of the sealing-ring transversely central thereof, substantially as set forth.

In testimony whereof I affix my signature in presence of two witnesses.

ANGELINE SMELKER.
